Fig. 8.

Inventor,

Frank X. Sturm.

By
Joseph A. Miettun
Attorney.

UNITED STATES PATENT OFFICE.

FRANK X. STURM, OF SHELBYVILLE, INDIANA.

WORKING GLOVE.

Application filed December 8, 1922. Serial No. 605,552.

To all whom it may concern:

Be it known that I, FRANK X. STURM, a citizen of the United States, residing at Shelbyville, in the county of Shelby and State of Indiana, have invented new and useful Improvements in Working Gloves, of which the following is a specification.

Working gloves with fingers have been made out of cloth with the palm and the 10 palm-side of the fingers reinforced with leather, but so far as I know, the back has been made out of separate finger pieces which were sewed and seamed together thereby requiring a great deal more of cloth 15 for the laps at the seams, and correspondingly more labor than if the back of the gloves were seamless. And so far as I am aware cloth working gloves have not been reinforced with or made of leather between 20 the fingers. Dress gloves have been made with leather distance pieces between the front and back, but these have required an extra gusset at each crotch, which is too expensive in the process of manufacture for 25 working gloves.

The object of this invention is to make a working glove with fingers and with a seamless back, out of cloth that will require less material and less labor in its production; 30 and a further object is to reinforce the palm and the palm-side of the fingers, and between the fingers with leather to increase the durability of the glove at those places where it is subjected to the greater wear.

I accomplish the above, and other objects which will hereinafter appear, by the means illustrated in the accompanying drawings, in which—

Fig. 1 is a blank or trunk of cloth from 40 which the body of the glove, without the cuff, is formed. Fig. 2 is a leather blank for reinforcing the palm, and fingers. Figs. 3, 4 and 5 are the leather distance pieces or fourchettes between the front and back material of the fingers. Fig. 6 is a cloth piece for the outside of the thumb. Fig. 7 is a leather reinforcement for the inner side of the thumb. Fig. 8 is a front view and Fig. 9 a back view of a finished glove for the 50 right hand.

Like characters of reference indicate like parts throughout the several views of the drawings.

In the trunk 10 shown in Fig. 1, the cloth 55 material for the palm and back of the hand is in one-piece integrally continuous at the

little finger portions, *d*, *d'*. In this form *a* represents the covering for the palm-side of the index finger and *a'* that for the back, *b* the covering for the palm-side for the 60 middle finger and *b'* for the back, and *c* the palm covering for the third finger and *c'* for the back. A cover for the palm-side of the thumb is formed at *e* by cuts oblique toward the seam joining the front to the 65 back at the index finger, the cut next to the seam being the longer of the two to cause the piece defined by the cuts to fold up in an opposite oblique direction. This trunk will make a glove for the right or left hand, according to which way it is folded, the fold being along a line from *x* to *y*. A reinforcement 11, of leather with fingers and thumb members corresponding in size and shape with those of the cloth trunk is placed outside on the palm of the folded trunk 10, and its edges are sewed into the seams where the front and back of the glove are directly joined. At the other places, mainly between each of the fingers, leather distance 70 pieces 14 of appropriate size and shape as illustrated in Figs. 3 to 5 inclusive are inserted and sewed into the corresponding seams, their proper locations being indicated by the usual marginal notches, as shown in 75 the drawings.

It will be noted that each of the fourchettes is widened on the line *n*—*n*, which occupies the crotch portion between the fingers and provides for the necessary fullness there, without the introduction of extra gussets such as are required and as are used in the manufacture of the much higher priced dress-gloves, but which would be prohibitive in cost for a cheap working-glove.

The thumb is reinforced by leather pieces of a shape illustrated in Fig. 7 which apply on the inner side of the thumb.

All of the fourchettes and the thumb reinforcements are made out of scrap leather 100 remaining after the large palm reinforcements shown in Fig. 2 are cut, and which would be waste material if not thus utilized.

In completing the glove it may be made with a cuff 12, as shown in Figs. 8 and 9, 105 with a leather wrist reinforcement 13, or the cuff may be omitted.

Having thus fully described my invention, what I claim as new and wish to secure by Letters Patent, is—

1. A glove comprising a one piece cloth trunk for the front and back of the glove

including finger pieces and adapted to be folded together on a line between the front and back of the little finger, and also having a thumb piece cut on lines oblique to the outside seam joining the front and back at the index finger the cut next to the seam being deeper than the other cut to make the folded thumb-piece oppositely oblique, a one-piece leather reenforcement for the palm and palm-side of the fingers having finger and thumb pieces corresponding in size and position with those of the palm side of the trunk, connecting means between the back finger-members of the trunk and the front members thereof and leather reenforcements, and members to complete the thumb portion of the glove.

2. A glove comprising a one-piece cloth trunk for the front and back of the glove including finger pieces and adapted to be folded together on a line between the front and back of the little finger, and also having a thumb piece cut on lines oblique to the outside seam joining the front and back at the index finger the cut next to the seam being deeper than the other cut to make the folded thumb-piece oppositely oblique, a one-piece leather reenforcement for the palm and palm-side of the fingers having finger and thumb pieces corresponding in size and position with those of the palm member of the trunk, and outside thumb pieces, and leather fourchettes each in one piece widest at the crotch connecting the front finger members of the trunk and their leather reinforcements with the corresponding back trunk members.

Signed at Shelbyville, Indiana, this the 4th day of December, 1922.

FRANK X. STURM.
